UNITED STATES PATENT OFFICE.

DANIEL BARDUA, OF MACK, OHIO.

SLIP-TONGUE ATTACHMENT.

SPECIFICATION forming part of Letters Patent No. 634,605, dated October 10, 1899.

Application filed August 21, 1899. Serial No. 727,909. (No model.)

To all whom it may concern:

Be it known that I, DANIEL BARDUA, a citizen of the United States, residing at Mack, in the county of Hamilton and State of Ohio, 5 have invented certain new and useful Improvements in Slip-Tongue Attachments; and I do hereby declare the following to be a full, clear, and exact description of the invention, reference being had to the accompanying 10 drawings, which form a part of this specification.

My invention comprises a slip-tongue attachment capable of being readily and securely applied to the ordinary clips of a front 15 axle of a vehicle after the shafts or thills have been detached from said clips. Said attachment includes a single undivided curved iron or bow, substantially semicircular in plan, and having at its rear ends eyes for the reception 20 of bolts, wherewith said bow is quickly coupled to the aforesaid axle-clips. Secured to the front or mid-length of this bow is a longitudinal socket, within which the butt-end of a tongue or pole can be readily fastened, 25 and mounted upon this socket is a transverse plate that supports a pivoted doubletree. By simply withdrawing a pin the pole is free to be slipped out of the socket before running the vehicle into a stable, and after bodily uncoupling the attachment a pair of shafts 30 can be fastened to the axle-clips, as herein-after more fully described.

In the accompanying drawings, Figure 1 is a plan of my slip-tongue attachment, a pole being omitted therefrom and the position of 35 a doubletree indicated by dotted lines. Fig. 2 is a vertical section of said attachment, the section being taken through the center of the socket and the butt-end of a pole being fastened within said socket. Fig. 3 is an enlarged transverse section of the socket, said section being taken in the plane of the doubletree-pivot. Fig. 4 is an elevation of the front end of the socket.

45 A represents the front axle of a vehicle, and a a' are clips for the attachment to said axle of a pair of shafts or thills in the usual manner.

B is a single undivided angle-iron, bent to 50 a practically semicircular shape and having at its rear ends eyes b b' for the reception of bolts C C', that couple this bow to the clips

a a'. Secured upon this bow and at its mid-length is the pole-socket above referred to, the principal members of said socket being 55 cheek-plates D D', that curve up and are then projected forward, the rear ends of these plates being bent laterally at d d' to enable their firm attachment to said iron B. Furthermore, these cheek-plates are not parallel, but converge toward the rear of the socket in order that a tapering butt-end of a pole or tongue may wedge therein when the team is backed. The front ends of the cheek-plates are formed into vertical eyes E E', as shown in Fig. 4, 65 for the passage of bolts e e', that clamp an upper cross-bar F and a lower cross-bar F' to said plates, this lower bar F' being provided with integral braces f f', that diverge rearwardly and are fastened to the bow B. The 70 upper cross-bar F has an integral rearwardly-projecting strap G, having a raised portion g and a downward bend g', the extreme lower end of this bend being secured between the cheek-plates by a transverse bolt g''. 75

H is a box-strap secured to the cheeks in the manner shown in Fig. 3, the horizontal terminations h h' of said strap having secured upon them a plate I, that supports a doubletree, (indicated by the dotted lines J.) 80

The dotted lines j j' indicate holdback straps or chains connecting the doubletree with hooks K K' of the bow B.

L is a bolt connecting the strap g and plate I and serving as a pivot for the doubletree, 85 a hook l being applied to this bolt for the attachment of a chain leading back to the vehicle-body. This chain is indicated by the dotted lines M and serves to support the pole attachment from said body m.

N is a pin passing through the strap G and entering a hole made vertically in the butt-end O of a wagon pole or tongue, and n is a chain connecting said pin with a staple n' of the upper cross-bar F. 95

P is a bolt passing vertically through the pole and adapted to bear against the cross-bars F F' when the team is backed, by which arrangement the cheek-plates D D' are relieved to a great extent from the wedging action of the pole-butt. 100

To apply this attachment to a vehicle, its shafts are first disconnected from the axle-clips a a', and then their bolts C C' are passed

through said clips and the eyes *b b'* of the bow *B*, thereby readily coupling the latter to the front axle *A*, and as the doubletree *J* is usually fastened to the plate *I* there is nothing more to be done than to fasten the chain *M* to the body *m*, insert the pole-butt *O* between the cheek-plates *D D'*, and pass the pin *N* through the strap *G* and down into said butt.

10 When the team is pulling, the strain comes upon the pivot *L*, and is thus transferred to the cheek-plates *D D'*, which plates in connection with the braces *f f'* have a drawing action on the bow *B*. This bow then pulls on the clips *a a'* and advances the vehicle; but when the team backs the bolt *P* bears directly against the cross-bars *F F'*, and the braces *f f'* then maintain the cheek-plates in a proper position and prevent them springing either to the right or left. Again, the four cross-bars *F F' H I* serve as ties that bind the cheek-plates together in a very secure manner, thereby rendering them mutually supporting and better able to resist the wedging action of the butt-end of the pole when the vehicle is backed.

20 Before running the vehicle into a stable the pole is slipped out of the socket formed by the members *D D' F F' H I*, and, if preferred, the chain *M* can be unhooked to permit the attachment being suspended from the front axle, or the device can be swung up and held by said chain from the vehicle-body *m*.

30 By reversing the above-described operations the attachment can be bodily removed and the shafts refastened to the vehicle. Finally, the hole *h''* in the cross-bar *H* is to permit the head of the pivot *L* being passed up through said bar before said head comes 40 to a bearing in the upper cross-bar *I*.

I claim as my invention—

1. A slip-tongue attachment including a single, undivided bow having an eye at each end; cheek-plates secured upon said bow; and

four cross-bars connecting said plates, the 45 rear, upper bar being perforated to admit a doubletree-pivot, all as herein described.

2. A slip-tongue attachment including a bow *B*, having a pair of eyes *b b'*; cheek-plates *D D'* secured upon said bow; four cross-bars *F F' H I*, connecting said plates; a strap *G* running back from the bar *F*, and provided with a raised portion *g*, and having its rear end fixed; and a doubletree-pivot *L*, connecting the plate *I*, and said raised portion *g*, all as 55 herein described, and for the purpose stated.

3. A slip-tongue attachment including a bow *B*, having a pair of eyes *b b'*; cheek-plates *D D'*, secured upon said bow; four cross-bars *F F' H I*, connecting said plates; a strap 60 *G g g'*, extending back from the cross-bar *F*, a doubletree-pivot *L* connecting the bar *I* and raised portion *g* of said strap; and braces *f f'*, extending from the cross-bar *F'*, to said bow *B*, all as herein described, and for the purpose stated.

4. A slip-tongue attachment including a single, undivided bow having an eye at each end; cheek-plates having lateral extensions secured upon said bow; and four cross-bars 70 connecting said plates, the rear, upper bar being perforated to admit a doubletree-pivot, all as herein described.

5. In a slip-tongue attachment including a single, undivided bow having a pair of cheek-plates mounted upon it, in the manner described, the box-strap *H* secured to the exteriors of said plates, and provided with horizontal extensions *h h'*, supporting a cross-bar *I*, traversed by a doubletree-pivot, all as 75 80 set forth.

In testimony whereof I affix my signature in presence of two witnesses.

DANIEL BARDUA.
